UNITED STATES PATENT OFFICE.

THOMAS J. CLARKE, OF JAMESTOWN, NEW YORK.

POWDER BOX.

Application filed March 10, 1927. Serial No. 174,255.

The invention relates to improvements in boxes whose primary use is for packaging face powder, and such invention deals with a known type of box, which embodies an inner container which is filled with the powder and is then housed within co-operable top and bottom sections of the box. Inner containers of this character are commonly formed with a bottom of paper and cardboard and are provided with a top having a comparatively large opening through which the container may be filled with powder. After this filling operation, the bottom section of the box is inverted and applied to what is then the upper portion of the filled container, the two being glued together. Then, when the article as so far completed is inverted, the top section of the box is applied. In this condition, the box of powder is marketed, and upon removing the top section of the box, the paper and cardboard which previously formed the bottom of the inner container, are accessible, so that they can be removed to give access to the powder. Boxes of the type above defined, have a very extensive use and are very desirable, but they are rather expensive to manufacture and quite an amount of material is necessarily cut out and wasted. Moreover, different purchasers of these boxes from the factory, require them in different sizes and with different sized openings in the tops of the inner containers and hence, a number of expensive dies must be kept on hand, to form these openings and to otherwise cut the blanks from which the inner container is constructed. Then too, in forming the side and end walls and the top of the inner container, it is customary to make use of a single cardboard blank, with the above mentioned opening cut from its central portion and with right angular notches cut in its corner portions, the parts of the blank between the notches being bent to form the side and end walls of the container. This manner of construction wastes the material cut from the corners of the blank and that cut from its central portion to form the opening. Moreover, when the container embodies these details of construction, it is prone to leak at the corners, permitting the powder to sift out.

It is the principal object of the present invention to provide a new and improved construction for the inner container, which is such as to minimize loss of material by cut-

ting, does not require special dies in order to form the filling opening in the top of the container, readily permits of assemblage by machine operations, and will be proof against leakage.

With the foregoing in view, the invention resides in the novel subject matter hereinafter described and claimed, the description being supplemented by the accompanying drawing.

Fig. 1 is a disassembled perspective view of the several parts from which the inner container is constructed.

Fig. 2 is a perspective view of the inner container completely assembled.

Fig. 3 is a vertical sectional view on line 3—3 of Fig. 2.

Fig. 4 is a vertical sectional view through a complete box embodying my improvements.

Fig. 5 is an elevation of the strip from which the outer frame of the inner container and top-forming flaps for said container, are formed.

In the drawing above briefly described, the numeral 6 designates an inner rectangular frame preferably bent from a single strip of cardboard to form opposed side and end walls 7 and 8, the ends of the strip being secured together by thinning one of them and gluing it to the other strip end, as indicated at 9. By forming the frame 6 in this manner, there is no danger of powder leakage at the corners thereof and its construction will also be simple, easy and inexpensive.

Preferably, a piece of cardboard 10 rests against the lower edge of the frame 6 to assist in forming a strong bottom therefor, and a sheet of paper 11 extends under this cardboard 10, being cut so as to provide it with four integral flaps 12. These flaps extend upwardly against the outer faces of the side and end walls 7 and 8 and have their upper portions bent inwardly as at 13, over the upper edges of said walls.

An outer rectangular frame 14 snugly surrounds the frame 6 and the flaps 12, said frame comprising opposed side and end walls 15 and 16 connected at the corners of the frame and provided at their upper edges with integral flaps 17, these flaps being turned inwardly and lying upon the inturned portions 13 of the flaps 12. These flaps jointly form a top for the inner container and they are preferably of such width as to leave a central opening 18 of desired size, through which the container may be filled with pow-

dér, said opening being usually of a size to accommodate an outlet nozzle of a well known form of box-filling machine.

In constructing the outer frame 14, I make use of a single cardboard strip such as that shown in Fig. 5. At spaced points, this strip has notches 19 formed in one of its edges to define the ends of the flaps 17, and these notches may be formed by an ordinary corner-cutting machine, instead of requiring that specially constructed dies be formed, to cut the strip in the desired shape. The strip is transversely scored at the notches 19, as indicated at 20, defining the ends of the side and end walls 15 and 16, and said strip is longitudinally scored at 21, from each notch 19 to the next notch, thereby defining the upper edges of said walls. By bending the strip upon the scored lines 20, and suitably connecting its ends, the outer frame 14 is formed with the flaps 17 then projecting upwardly. Preferably, a thin strip of paper 22 is glued around the frame 14 to hold the strip ends together and to give a more finished appearance to this portion of the frame, which later is exposed when the complete box is opened.

With the frame 14 standing as seen in Fig. 1, the paper sheet 11, the piece of cardboard 10, and the inner frame 6, may be forced into it from above, by machine operations, said inner frame 6 serving to downwardly move the cardboard 10 and the paper 11 into the frame 14. During this operation, the flaps 12 will obviously be upwardly folded between the walls of the inner and outer frames and they will project above these frames at the inner sides of the flaps 17. Thus, when these flaps are folded over to jointly form a top for the inner receptacle, the projecting portions of the flaps 12 will be similarly folded as indicated at 13 in Fig. 3, so that there is no danger of the flaps 12 pulling out from engagement with the inner and outer frames, although not glued thereto.

The inner container as above described, is filled through the opening 18, while it stands as seen in Figs. 2 and 3. After filling, the bottom section B of an outside box is inverted and slipped onto the upper portion of the filled receptacle, as indicated by dotted lines in Fig. 3, said bottom section being glued either to the flaps 17 or to the side and end walls of the outer frame 14. Now, the entire filled assemblage is inverted and the top section T of the outside box is slipped over the portion of the frame 14 projecting beyond the bottom section B. In this condition, the package is marketed.

When a purchaser of a box of the powder, wishes to open the same, she removes the top T, tears or cuts the paper 11 and removes the cardboard 10, thus giving access to the powder.

Excellent results have been obtained from the details disclosed and they are therefore preferably followed. However, within the scope of the invention as claimed, variations may be made. In this connection, attention is invited to the fact that while the flaps 17 are preferably of such proportions as to leave the opening 18, they might in some instances be wider so as to form a complete top for the inner receptacle, provided with no opening. With this construction, it would of course be necessary to fill the container with the powder while the flaps stood upright, folding said flaps inwardly, into co-operative relation, after filling.

I claim:

1. In a powder box, an inner container comprising an inner frame consisting of opposed side and end walls connected in a powder-tight manner at the corners of the frame, an easily rendible top sheet extending over said frame and having integral flaps which extend downwardly against the outer faces of said side and end walls, and an outer frame surrounding said inner frame and flaps, said outer frame consisting of opposed side and end walls connected at the corners of the frame and having integral flaps at their lower edges which are turned inwardly under the lower edge of the inner frame and project horizontally inward from said inner frame; and an outer container snugly receiving said inner container, said outer container having a fixed bottom section co-operable with said horizontal flaps in forming the box bottom, and a removable cover giving access to said easily rendible top sheet.

2. In a powder box, an inner container comprising an inner frame consisting of opposed side and end walls connected in a powder-tight manner at the corners of the frame, an easily rendible top sheet extending over said frame and having integral flaps which extend downwardly against the outer faces of said side and end walls, are turned inwardly under said walls and project horizontally inward from the latter, and an outer frame surrounding said inner frame and flaps, said outer frame consisting of opposed side and end walls connected at the corners of the frame and having integral flaps at their lower edges which are turned inwardly and lie horizontally under the aforesaid inwardly turned portions of said flaps of the top sheet; and an outer container snugly receiving said inner container, said outer container having a lower section co-operable with said flaps in forming the box bottom, and a removable cover section giving access to said easily rendible top sheet.

In testimony whereof I have hereunto affixed my signature.

THOMAS J. CLARKE.
